UNITED STATES PATENT OFFICE

GIANNI BETTINI, OF NEW YORK, N. Y.

PORTABLE LIGHTER

Application filed October 1, 1927. Serial No. 223,304.

This invention relates to portable lighters, and with respect to its more specific features, to lighters employing a sparking member as, for instance, a particle of a pyrophoric alloy.

Among the objects of the invention are the provision of a lighter of the character described which is convenient and efficient in operation and in which but one manipulative operation is required to effect ignition; in which the chance of leakage of fuel and consequent contamination of the person is minimized, and in which adjustment of the sparking apparatus, especially of the sparking particle, is facilitated.

Other objects of the invention will be in part obvious and will in part appear hereinafter.

The invention accordingly comprises the features of construction, combination of elements, and arrangement of parts, which will be exemplified in the construction herein-after set forth and the scope of the application of which will be indicated in the claims.

For a fuller understanding of the nature and objects of the invention reference should be had to the following detailed description taken in connection with the accompanying drawings, in which

Fig. 1 is a perspective view of one embodiment of the invention.

Fig. 2 is a plan view looking at the top of the lighter.

Fig. 3 is a vertical section on the line 3—3 of Fig. 2.

Fig. 4 is a side elevation of the upper portion of the lighter, partly in section to show details.

Fig. 5 is a view similar to Fig. 4, but taken from the opposite side of the lighter.

Fig. 6 is a cross section of the upper part of the lighter taken on the line 6—6 of Fig. 2.

Referring now more specifically to the drawing, the numeral 1 indicates the frame and metal fuel reservoir. The fuel in the reservoir may be kerosene. Extending into the reservoir is the wick 2, which projects through the nipple 3 of the top of the reservoir, the upper end of the wick being disposed to be lighted from sparks produced by

the sparking apparatus. In addition to the kerosene, the reservoir may contain a mass of absorbent cotton or other suitable absorbent material. In the bottom of the reservoir is a filling opening closed by a removable plug 55 3'. On the side wall of the reservoir a large glass mirror 4 may be placed. One end of the reservoir may have an opening 5 communicating with a lip stick receptacle 6 sealed from the fuel content of the reservoir, and 60 adapted to be closed by a cap 7.

The sparking apparatus includes the sparking particle, or member, 8, as for instance a particle of a pyrophoric alloy containing cerium and iron. The sparking apparatus also 65 includes an abrader 10 which, in the embodiment illustrated, is a steel disk or wheel, roughened on its periphery, as by the teeth 11, for more effectively abrading the sparking particle 8. In the embodiment illustrated 70 the abrader 10 is fixed to the upper end of an abrader shaft 12, which latter is journaled for rotative movement in the upper end of the reservoir and is encircled by a helical spring 13, one end of which spring is fixed to the shaft 12, the other end being fixed to the frame as, for instance, to the under side of the top of the frame at 14. As will more 75 fully be explained hereafter, one purpose of the spring 13 is to effect rotation of the abrader 10 in contact with the sparking particle 8 so as to produce sparks, the rotation being in a direction so that the sparks will be projected toward the upper end of the wick 2 so as to ignite the wick. In this wise the 80 spring 13 serves as a motor and expends energy to effect relative movement in one direction between the members 8 and 10 to produce sparking.

The numeral 15 indicates a lever fixed to 90 the operating member, or abrader, 10, and which is manually operable to rotate the shaft 12 in the direction to wind up the spring 13, and thereby potentialize the latter so that its reactive effect shall compel spark-effecting 95 rotation of the abrader 10 as just explained. In the present embodiment the spring 13 is always under sufficient tension quite strongly to retract the lever 15 until it is arrested as, for instance, by contact with some fixed por- 100

tion of the lighter, said portion in the present embodiment being the channel member 16, to be further described, or a part of or connected to the top of the reservoir. When the lever 15 is moved from the full line position to the dotted line position illustrated in Fig. 2, the spring 13 is further potentialized, as will be understood.

The numeral 17 indicates the wick cover, which may be a cup or thimble-like member into which the upper end of the wick may enter when the cover is in closed position, as illustrated in Figs. 1 and 4, and the mouth of the thimble may closely contact with the upper face of the nipple 3, so as completely to enclose the upper end of the wick, thus minimizing exuding of fuel through the joint between the cover and nipple; also it will be understood that the cover extinguishes the flame of the wick.

For moving the wick cover to open position, illustrated in the dotted line in Fig. 4, a cover opening device is provided. In the present embodiment the cover opening device includes a cover supporting arm 18, pivoted for oscillatable movement in an upstanding bearing 19 by being fixed to a rotative pin 20 passing through said bearing. The numeral 21 indicates a spring disposed in a chamber, or tube 22, depending from the top member, or plate 23, of the reservoir, the lower end of the chamber being closed and supporting one end of the spring 21. Projecting through a small opening in the plate 23 is a covering actuating pin 24, the base of which rests on the top of the spring 21 and is enlarged to limit the upward movement of the pin 24. The pin 24 is disposed to coact with the cover supporting arm to one side of the pivotal axis of said arm.

In the present embodiment the arm 18 has a depending lug, or hub 26, against which said pin is adapted to contact so as to urge the cover toward open position. As illustrated in Fig. 4, the hub has a flat face 27 which, when the cover is in open position, rests against the top 23 and limits opening movement of the cover. From the flat face 27 the hub continues in a gradual curve or cam-like face to another flattened portion of the hub indicated at 28 to one side of the pivotal axis, the pin 24 being adapted to contact the latter face to one side of the pivotal axis when the cover 17 is closed. When the hub 26 moves in a direction to close the cover, the cam-like face effects gradual compression of the spring 21 by moving the pin 24 downwardly, the spring 21 being relatively strongly compressed when the cover is closed. It will be seen therefore that, when the cover is free to open, its opening movement will be spring actuated, by expansion of the spring 21.

In the present embodiment a latching mechanism is employed and is adapted to

latch the wick cover in closed position. As illustrated in Fig. 5, the latching mechanism includes a latch member 29 fixed to oscillate with the pin 20 and being pivotally movable with the cover through its connection with the cover arm 18. When the wick cover is closed, the latch arm 29 is in the position illustrated in Fig. 5 with its upper edge 30 adapted to lie underneath the lever 15. When the wick cover 17 is in closed position, retraction of the lever 15 by the spring 13 to the full line position illustrated in Fig. 2 causes said lever 12 to be positioned immediately above latch member 29, so that the lever 15 cooperates with the member 29 to latch said cover in closed position, the lever 15 thus also acting as a latch member and preventing pivotal movement of the latch member 29 in cover opening direction under the influence of the spring actuated cover opening device.

The sparking particle 8 comprises a small cylindrical piece of pyrophoric alloy disposed in the channel 16, which channel consists of a tube fixed to the upstanding portion 19 of the top of the reservoir. For pressing the particle 8 into sparking position in contact with the abrader 10 a helical spring 31 is disposed in the channel 16 behind said particle. At the opposite end of the channel from the particle 8 is the nut 32 having screw threaded engagement with the inner wall of the channel 16, (Fig. 3) rotation of said nut being adapted to compress the spring 31 and more or less tension it so that the pressure between the particle 8 and the abrader 10 may be varied as desired. The nut 30 is provided with an extensible handle for facilitating its adjustment. In the embodiment illustrated a squared shaft 33 loosely passes through a counterpart squared opening in the nut 32 and at one side of the nut enters the helical coil of the spring 31. At the opposite side of the nut from the spring the shaft 33 is provided with a knurled head 34 by which it may be conveniently and effectively gripped and actuated.

In the position illustrated in Fig. 3 the head 34 of the shaft 33 is close to the knurled flange 35 of the nut 32. By grasping the head 34, the shaft 33 may be drawn to the dotted line position indicated in Fig. 3, and in this extended position rotation of the shaft 33, and consequently of the nut 32, is very conveniently accomplished, thus effecting adjustment of the tension of the spring 31. After the spring 31 has been so adjusted, the head 34 may be pushed to the right (Fig. 3) so as to be out of the way. Furthermore, it will be noted that when the particle 8 is to be replaced by another particle, the nut 32 may be conveniently removed by drawing the shaft 33 through the nut to its outer position and then rotating said shaft to turn off the nut from the chan-

nel 16. By then moving shaft 33 so as to project from the opposite side of the nut, the spring 31 may be shifted thereover and with the shaft and nut introduced into the bore of the channel and turned into place.

5 When the lighter is not being used it may be conveniently carried in the pocket, and at such time the wick cover will be in closed position and the lever 15 will be in retracted position close alongside the channel 16, in which position the lever will be held by the spring 13, with its free end conveniently accessible for contact and actuation by the finger of the operator, whether the cover be 10 open or closed. Also under such circumstances, the wick cover will be held closed by the lever 15, acting as a latch member, and coacting to prevent cover opening movement of the latch member 29. The lighter may conveniently be held and actuated by one hand. 15 While so holding the lighter, the end of the lever 15 may be pressed toward the dotted line position (Fig. 2) by the thumb or finger of the operator, and such movement of the lever 15, will unlatch the latching mechanism, the lever 15 disengaging from the latch member 29 shortly after the movement of the lever 15 is started. Thus the cover will be freed for opening and the cover opening 20 mechanism will automatically rotate the arm 18 and the cover carried thereby to open position. Outward movement of the manually operated lever 15 will also potentialize the spring 13 to a sufficient degree, whereupon 25 the finger is removed, permitting said lever to fly back under the influence of said spring 13, and with the result that the abrader 10 will be given a quick rotative abrading movement by the spring 13. In consequence of the quick movement, the sparking apparatus 30 will be actuated, sparking will result, and the sparks will be projected toward the now open wick, which latter will be ignited. It will be noted that repeated manual operation of the lever 15 is possible at the will of the operator, while the wick cover is in open position and without moving said cover to closed position. It will, furthermore, be noted that when the latch member 29 is moved by the 35 cover opening mechanism, said member 29 is moved to a position between the manually operable lever 15 and the channel 16, so that spring retracted movement of the lever 15 will be arrested by the latch member 29, and that further movement of the lever 15 will be required before it reaches latching position. By applying the thumb to the cover 15 or the arm 18, the cover may be closed at will, whereupon the spring 13 will effect further 40 movement of the latch lever 15 and to cover latching position cooperating with the latch member 29, which latter will then be held in position to retain the cover closed. In this wise, once the cover is latched closed, 45 relative movement between the abrader and

the sparking member by manual power is required to effect unlatching, and consequent opening of the wick cover. When held in the pocket there is practically no chance of accidental spark actuation of the lighter. 70 Furthermore, the cover will positively be latched in closed position, thus protecting the person from contamination by the liquid fuel employed. It will be seen that the spring actuated sparking actuation of the 75 lighter is engendered by a preliminary, or partial manipulation of the lever 15, the one following the other in the operation of effecting sparking, so that movement of the finger of the operator is simple and need not 80 be quick.

Having described my invention, what I claim as new and desire to secure by Letters Patent is:

1. A lighter of the character described, including, in combination, sparking apparatus including a sparking member and an abrader adapted for relative movement therebetween to produce sparking, a spring adapted to expend energy to effect relative movement between said sparking member and abrader to produce sparking, a wick cover adapted to open and close, and means, including two members one of which is driven by said spring, adapted to cooperate with each other to latch 90 the cover closed, said two members movable relative to each other to effect unlatching, the one member into position to arrest movement of the spring driven member to latching position. 95

2. A lighter of the character described including, in combination, a sparking apparatus including a sparking member and an abrader adapted for relative movement therebetween to produce sparking, a wick 105 cover adapted to open and close, cover latching mechanism including a latch lever, a spring for moving said lever to latching position, means whereby movement of said lever from latching position is adapted to wind up said spring and means whereby said relative movement is adapted to be effected by expenditure of energy of said spring. 110

3. A lighter of the character described including, in combination, a sparking apparatus including a sparking member and an abrader adapted for relative movement therebetween to produce sparking, a wick cover adapted to open and close, cover latching mechanism including a latch lever, a spring 115 for moving said lever to latching position, means whereby movement of said lever from latching position is adapted to wind up said spring, means whereby said relative movement is adapted to be effected by expenditure 120 of energy of said spring, and a spring actuated cover opening device. 125

4. In a lighter of the character described, in combination, an oscillatable wick cover, a 130 cover actuating means, cover latching mech-

anism, a sparking apparatus including a movable operating member spring actuated to effect sparking, and means whereby, when the cover is latched closed, actuation of said operating member unlatches said latching mechanism.

5. In a lighter of the character described, in combination, an oscillatable wick cover, a cover actuating means, cover latching mechanism, a sparking apparatus including a movable operating member spring actuated to effect sparking, means whereby, when the cover is latched closed, actuation of said operating member unlatches said latching mechanism, 10 said cover actuating means comprising a pivoted cover arm, and a spring actuated pin adapted to urge said cover toward open position, said pin coacting with said cover arm to one side of its pivotal axis.

15 20 In testimony whereof I affix my signature.
GIANNI BETTINI.
